UNITED STATES PATENT OFFICE.

DAVID WEISSBERG, OF PITTSBURGH, PENNSYLVANIA, ASSIGNOR OF ONE-HALF TO
MAX WEISSBERG, OF PITTSBURGH, PENNSYLVANIA.

TRUNK-LOCK.

1,122,224.

Specification of Letters Patent. Patented Dec. 22, 1914.

Application filed April 20, 1914. Serial No. 833,115.

To all whom it may concern:

Be it known that I, DAVID WEISSBERG, a citizen of the United States, and resident of Pittsburgh, in the county of Allegheny and State of Pennsylvania, have invented a new and useful Improvement in Trunk-Locks; and I do hereby declare the following to be a full, clear, and exact description thereof.

10 My invention relates to improvements in locks for baggage and is particularly, though not exclusively, concerned with an improved form of lock for a trunk.

15 The object of the invention is to provide means to prevent unauthorized opening of the trunk by the unlocking or forcing of the usual trunk lock.

20 A further object is to so construct the safety-lock, as it may be called, that it will not in any way interfere with the usual manner of locking the trunk, and when not in use may be entirely concealed.

25 With these objects in view the invention consists of the constructions and arrangements of parts, preferred forms of which are illustrated in the accompanying drawings, in which—

30 Figure 1 is a fragmentary view of a part of a trunk showing the invention applied thereto and in open position; Fig. 2 is a perspective view similar to Fig. 1 showing the device in locked position.

35 Referring to Figs. 1 and 2, the escutcheon 1 of the trunk lock may be of the usual form and may be secured as usual to the lid 2 thereof. A hasp may also be of usual form and comprises the base 3 riveted to the body of the trunk 4, and having the hinged hasp portion proper 5 which may 40 be locked to the escutcheon through the key hole 6 in the usual manner.

45 In order to prevent unauthorized opening of the trunk even though a party may hold a duplicate key or skeleton key by which the article or trunk locked could be forced, I provide an extra locking means consisting in the instance here shown of a staple 7 hinged to the lid of the trunk as at 8 and I

provide a slot 9 in the hasp through which this staple when turned at right angles to 50 the lid may be passed and may be engaged by a padlock 10. Thus even though the trunk lock proper is forced, it will be impossible to gain access to the trunk without wrenching off the hasp. While I have 55 shown the slot or opening 9 for the reception of the staple 7 extending longitudinally of the hasp it may be obviously arranged transversely thereof and the staple 7 may be shifted at right angles to its position 60 shown in Fig. 1 to enter such opening.

In the modified form of the invention shown in Fig. 3, the locking staple 11 is attached directly to the outside of the hasp 12 and above the escutcheon 13 on the lid 14 is mounted a second hasp 14 hinged at 15 to its base 16, also attached to the lid and the hasp is provided with an opening 17 to receive the staple 11. It will be seen that in this form of the invention the key hole of 70 the regular trunk lock is entirely concealed and is inaccessible to unauthorized use.

In the modified form shown in Fig. 4, the hasp 18 is slightly off-set, as at 19, to space it away from the trunk lid to accommodate a locking bale or strap 20 secured to the lid and having the apertured ears 21 adapted to receive the shackle 22 of the padlock. The neck or off-set portion 19 of the hasp is also made considerably narrower 80 than the locking end thereof, so that the locking head thereof cannot be slipped through the locking bale 20.

While I have herein described the particular embodiments of my invention, it is 85 understood that the same may be altered in details and relative arrangement of parts within the scope of the appended claims.

What I claim is:

1. In a baggage lock, the combination 90 with a locking hasp, of an auxiliary lock comprising a staple and padlock whereby said hasp may be held in locking position independently of its usual locking mechanism, said staple when not in use being arranged to be concealed by the hasp. 95

2. In a trunk lock, the combination with coöperating locking members, upon the body and lid of the trunk including a locking hasp, of an auxiliary locking member
5 adapted to engage the hasp when in locked position whereby the locking of the trunk may be secured independently of the usual locking mechanism, said member being ar-

ranged to be protected against being broken off, by said hasp.

In testimony whereof, I the said DAVID WEISSBERG have hereunto set my hand.

DAVID WEISSBERG.

Witnesses:
